UNITED STATES PATENT OFFICE.

ROUGHSEdge WALLWORK AND ARTHUR COLLINGS WELLS, OF
MANCHESTER, ENGLAND.

PNEUMATIC PAINTING APPARATUS.

SPECIFICATION forming part of Letters Patent No. 577,522, dated February 23, 1897.

Application filed March 23, 1896. Serial No. 584,504. (No model.) Patented in England May 3, 1894, No. 8,839.

To all whom it may concern:

Be it known that we, ROUGHSEdge WALLWORK and ARTHUR COLLINGS WELLS, subjects of the Queen of England, residing at 5 Manchester, in the county of Lancaster, England, have invented certain new and useful Improvements in Pneumatic Painting Apparatus, (for which we have obtained Letters Patent in Great Britain, dated May 3, 1894, 10 No. 8,839;) and we do hereby declare the following to be a full, clear, and exact description of the invention, such as will enable others skilled in the art to which it appertains to make and use the same, reference being had 15 to the accompanying drawings, and to letters and figures of reference marked thereon, which form a part of this specification.

Our invention has relation to the art of applying paint and other similar more or less 20 fluid or viscous bodies, as tar and the like, mechanically to walls and other surfaces; and it has for its object the provision of simple and convenient means, easy of manipulation and control and of great efficiency, whereby 25 not only the work of the ordinary coating of a surface with paint or the like may be thoroughly, rapidly, and efficiently effected, but whereby more or less artistic effects in shading and in the blending of colors may be produced.

Referring to the accompanying drawings, Figure 1 is an elevation of an apparatus embodying our invention, a portion of the standard for the driving-shaft of the air-compressor 30 being broken away, showing the same hollow and serving as a storage-chamber for compressed air. Fig. 2 is a half-elevation and half-section of a tank for compressed air containing the receptacle or can for the paint or 35 the like. Fig. 3 is a half-plan and half-section thereof. Fig. 4 is a detail sectional view of the connection between the paint-delivery duct of the aforementioned tank and the flexible pipe or hose carrying the spraying nozzle 40 or ejector. Fig. 5 is a detail sectional view of the paint-stirring device and its handle constructed to perform the function of paint-delivery duct, to which the flexible pipe or 45 hose carrying the spraying-nozzle is adapted.

to be connected. Figs. 6, 7, and 8 are detail 50 sectional views of spraying nozzles or ejectors, and Fig. 9 is a side elevation of Fig. 6.

Similar symbols of reference indicate like parts wherever such may occur in the figures of drawings just described.

Our improved apparatus comprises, broadly speaking, a suitable source of compressed-air supply, a tank for compressed air adapted to contain one or more receptacles or cans for paint or the like, a spraying-nozzle, and suitable connections between the air and paint passages of said nozzle and the sources of compressed-air and paint supply.

The air-compressor illustrated in Fig. 1, although of a very simple and compact construction, is, however, not absolutely necessary to the operation of our apparatus, as any other construction of compressor or any suitable source of compressed-air supply may be used in connection with the other parts of 65 our said apparatus, said compressor being simply shown as an example of a convenient source of compressed-air supply, and said compressor may be stationary and operated from a steam or other suitable engine or by 70 hand, or it may be a portable hand-operated compressor, according to the requirements of use.

Referring now to Fig. 1, the compressor consists of a hollow standard S, provided with 80 a union coupling s, having a pressure-gage s', and a blow-off valve s², and a branch s³, to which latter is coupled one end of a flexible pipe or hose P'. At its upper end the standard S has suitable bearings for a driving-shaft S', carrying a loose and fast belt-pulley p and p' or a crank-handle h, or both, as shown, and a fly-wheel w, to the wrist-pin of 85 which is journaled the connecting-rod r of the compressing ram or piston, working in a cylinder C on the base s⁴ of standard S, the compressor-piston being of any usual or well-known construction and provided with a suitable valve or valves arranged to open on the upstroke and close on the downstroke, 90 thereby forcing the air drawn in on the upstroke through a suitable passage at the foot 95 of the cylinder C into the hollow standard S.

Inasmuch as the construction of compressor-piston is one well known, we have deemed it unnecessary to illustrate the same in detail.

Referring now to Figs. 2 to 5, inclusive, T 5 indicates a tank provided near its bottom with a valved branch t , adapted to receive a T-coupling t' , Figs. 1 and 3, to which are connected the flexible pipe P' , leading to the source of compressed-air supply, namely, the standard S, and a flexible pipe P^2 , connected with the air-passage in the spraying-nozzle N, Fig. 1, as hereinafter more fully described.

The tank T is constructed with a contracted neck t^2 , having projections or brackets t^3 , that 15 form supports for the rim, swell, or flange c' of a receptacle or can C' for the paint. By suspending the receptacle C' within the tank T for said compressed air, said receptacle being of less diameter than the interior diameter of the tank, a space is left around the receptacle, so that the compressed air can effectually act upon the surface of the paint without exerting undue pressure upon the receptacle itself, as will be readily understood. The contraction of the neck of the tank T forms an offset or shoulder, from which project perforated lugs t^4 , arranged in pairs and forming bearings for T-shaped bolts t^4 , the stems of which are screw-threaded for the 25 reception of winged or so-called "butterfly" nuts n^2 , by means of which the cover T' is secured to the tank T, said cover being provided with slotted projections t^5 for the stem of the bolts and with an annular groove into 30 which fits the contracted neck or upper end t^2 of the tank, a packing-gasket 22 being seated in said groove in order to provide an air-tight joint between the tank and its cover T'. The latter is further provided with a 35 branch t^6 and with a screw-threaded socket leading to said branch, into which socket is secured the paint-delivery pipe P^3 , that extends nearly to the bottom of the paint-receptacle C', Fig. 2. To the branch t^6 is coupled one end of a flexible pipe P^3 , whose other 40 end is coupled to the spraying-nozzle N in such manner as to conduct the paint to the paint passage or channel in said nozzle, as hereinafter described. The cover T' is further provided with a central stuffing-box t^7 for the passage of the stirrer-shaft S², provided with a plurality of stirring or agitating blades b^2 , a tight joint being formed by means of a 45 suitable packing in the stuffing-box and a stuffing-box gland t^8 , screwing into said stuffing-box in a well-known manner. To the outer end of the stirrer-shaft S² is secured a handle H², by means of which the said shaft can be oscillated or rocked for the purpose 50 of agitating the paint in receptacle C' from time to time, as may be required and for a well-known purpose. It will be seen that by unlocking the cover T' and removing the same the stirrer is also removed, and ready 55 access is had to the paint receptacle C'. The cover T' is further provided with a blow-off plug T² or a valve and with a pressure-gage T³.

For the purpose of preventing solid matter in or skin that may form on the paint in receptacle C' from reaching the spraying-nozzle N, and in order that the flexible paint-conveying pipe may be easily connected with the paint-delivery branch t^6 in the cover T' of the can, we provide a removable coupling D, adapted to screw into branch t^6 , Fig. 4, said coupling being divided into two chambers 2 and 3 by a partition 4, an interiorly-threaded branch 5 communicating with chamber 3 through the open or perforated bottom of the partition 4. Into the branch 5 screws a strainer-plug 6, whose lower open end seats on the bottom of partition 4 around the openings or perforations in said bottom, so that all the paint forced through the branch t^6 by the pressure of the air in tank T is compelled to flow through the strainer-plug 6 before reaching the outlet branch 7 of the coupling D, and as the strainer 6 is readily removed from said coupling there is no difficulty in freeing the same from solid matter lodged therein. If desired, the branch t^6 may be provided with a stop-cock or valve V, Fig. 4, for the purpose of cutting off the supply of paint from the coupling in case it should become necessary to cleanse the strainer while the apparatus is in operation.

The outlet of the coupling D is a stuffing-box 7, into which screws a hollow gland 8, that is provided with a handle 9 for manipulating said gland, and through the latter and the packing 12 in the stuffing-box 7 extends a pipe 13, to which the flexible paint pipe or hose P^3 is coupled, so that the latter pipe can be readily removed from the coupling D by unscrewing the gland 8 and as readily applied and a tight joint maintained. The delivery branch t^6 and paint-delivery pipe P^3 may be dispensed with and the dasher or stirrer shaft S² and its handle H² may be employed for the delivery of the paint from the receptacle C', as shown in Fig. 5, in which case the dasher or stirrer shaft S² is made hollow, as well as a portion of the handle proper, h, which is screw-threaded interiorly for the reception of the strainer-coupling D.

The compressed-air-inlet branch t for the tank T is provided with a needle-valve V' for the purpose of regulating the pressure in the said tank, and consequently the volume of paint delivered to the spraying device.

The last-named device is susceptible to various structural changes, the construction depending in a measure upon the nature of the substance to be sprayed, more particularly to the degree of viscosity or fluidity of such substance, and also upon the grade or nature of the work. Thus, for instance, when a comparatively liquid paint is employed, and particularly when the coloring is to be graduated or shaded, the construction of the spraying device will be somewhat different from that of a spraying device adapted to spray semi-fluid materials, or viscous materials, like tar.

In Figs. 6, 7, and 9 we have shown spray-

ing devices adapted to the use of the more fluid paints and for the higher grades of work.

The spraying device N consists of a casting E, in which are formed two passages e e' for compressed air and paint, respectively, said passages leading to coupling branches e^2 e^3 , into which are screwed the air and paint pipes P^{22} P^{23} , that terminate in a flanged hollow screw-plug 14, onto which screws a coupling-sleeve 15 on the flanged end of couplings 16, to which the flexible pipes or hose P^2 and P^3 are respectively coupled in a well-known manner.

The pipes P^{22} P^{23} , which serve as a handle for the spraying device N, are rigidly connected together by suitable brace or connecting blocks 17 and 17^a, and from said pipes projects a stop-arm 18. The block 17^a has a bearing for the fulcrum-pin of a toothed sector-lever L, the arm l of which is held normally to the stop-arm 18 by a coiled spring on its fulcrum or by a spiral spring 19, connected with said arm l and with the stop-arm 18, respectively.

The flow of paint through passage e' is controlled by a stop-cock or valve v' , on the spindle of which is secured a pinion e^4 in gear with the toothed sector-arm l' of lever L. The casting E is further provided with a transverse passage e^5 on a line with a blow-off branch e^6 and intersecting the paint-passage e' and its valve v' , so that when the valve is properly positioned communication can be established between the blow-off branch e^6 and passage e for air through the valveway for the purpose of clearing said valveway of any solid matter that may lodge therein and tend to clog or choke up the same.

When the lever L is in its described normal position, the valve v' is fully open, as shown in Fig. 6, and as the connected pipes P^{22} and P^{23} are preferably rigid, as stated, serving as a handle for the spraying device, the operator is enabled with his thumb or forefinger under the arm l of the lever L to readily and conveniently control the flow of paint through passage e' .

The casting E has two concentric screw-threaded bosses, on the outer one of which is screwed the paint-nozzle n' and to the interior smaller boss the air-nozzle n . The outer end or mouth of the paint-nozzle is screw-threaded interiorly for the reception of a spraying-nozzle n^3 , having a conical or tapering bore, the smaller end of the said nozzle facing the like end of the air-nozzle n , the air and paint passages e and e' communicating with said nozzles n and n' , respectively. By means of the auxiliary spraying-nozzle n^3 the paint supplied thereto under the action of the compressed air is thoroughly and completely atomized or sprayed, and by varying the supply of paint beautiful and uniform shading or grading of colors can be readily obtained with very little practice. The casting E is further provided with a hook h^3 , so that the spraying device can be hung up and the paint

allowed to flow back through the paint channels and pipes when the spraying device is not in use.

It will be observed that all the parts of which the spraying device is composed are detachably connected together, so that the cleansing of the same is readily effected.

Instead of inclosing the air-nozzle in the paint-nozzle, as shown in Fig. 6, the paint-nozzle may be inclosed in the air-nozzle, as shown in Fig. 7.

In the use of less fluid paints or when tar or similar substances are to be sprayed we dispense with the auxiliary nozzle n^3 , as shown in Fig. 8, and, if desired, the paint passage or channel e' may be directly connected with the paint-pipe P^3 , and the latter may be directly introduced into a paint pot or can, as, for instance, when the apparatus is used at great elevations, as on scaffolding in front of buildings, ships, or the like, to avoid the forcing of the paint through long lines of pipe, and, as the spraying device shown in Figs. 6 to 8 operates in the same manner as an ordinary lifting and forcing injector, the paint is readily drawn into the spraying device from the pot or can near at hand, and the supply can be readily controlled by means of the stop-cock or valve v' , which may in this case be provided with the usual handle.

In view of the construction of the spraying device it is obvious that the paint may be forced even through long lines of piping under a comparatively low air-pressure, the injector, or, more properly speaking, the ejector, spraying device assisting the flow of paint very materially.

We have hereinbefore stated that both the tank T and the spraying device are supplied with air under pressure from the compressor-reservoir. It is obvious, however, that the said spraying device may be supplied with air from the tank; and the details of construction may also be varied without departing from the nature of our invention, while the tank T may be mounted on wheels for purposes of ready transportation.

Inasmuch as the pressure of the air supplied to the spraying-nozzle may be readily controlled and the force under which the paint is ejected from said device regulated, it is obvious that said paint may be driven from the nozzle with sufficient force to effectually penetrate all recesses or inequalities in the surface to be painted, thereby effecting a great saving in labor as compared with hand-painting.

We have hereinbefore described and shown in the drawings as a convenient and preferred arrangement an open paint-pot suspended within a tank adapted to contain air under pressure. It is, however, obvious that this arrangement is not absolutely necessary, substantially the same results being obtained by allowing the paint-pot to stand on the bottom of the tank and providing any suitable and well-known means for holding such pot

against displacement. We have also described means whereby obstructions in the paint-valve v' may be removed by placing said valve in communication with the atmosphere through a blow-off branch e^6 and with the passage e for compressed air through a passage e^8 . It is obvious that these connections may be dispensed with, and solid matter entering the valve-passage on the feed side may be removed by imparting to the valve v' a complete revolution, so as to reverse the position of its passage relatively to the feed-pipe, whereby solid matter lodging in one end of the valve-passage will be forced out by the paint itself by reversing the position of the valve through the medium of the rack and pinion $e^4 l'$, as will be readily understood.

Having thus described our invention, what we claim as new therein, and desire to secure by Letters Patent, is—

1. An apparatus such as described, comprising a spraying device provided with a paint and an air duct, a closed tank, an open paint-receptacle therein and a paint-passage leading from the paint-receptacle to the paint-duct in the spraying device, in combination with an air-compressor, a storage-chamber for the compressed air, mechanism for operating

the compressor carried by said chamber, and means for conveying the compressed air from the storage-chamber to the aforesaid tank and to the air-passage in the spraying device, respectively, for the purpose set forth.

35 2. An apparatus such as described, comprising a spraying device provided with a paint and an air duct, a closed tank, an open paint-receptacle therein and a paint-passage leading from the paint-receptacle to the paint-duct in the spraying device, in combination with an air-compressor, a storage-chamber for the compressed air, mechanism for operating the compressor carried by said chamber, flexible pipes connecting the storage-chamber with the aforesaid tank and the latter with the air-duct in the spraying device, for the purpose set forth.

3. An apparatus such as described comprising a spraying device provided with a paint and an air passage, a closed tank, an open paint vessel therein, a paint-duct leading from near the bottom of the paint vessel to the outside of the tank, and a flexible pipe connection between said paint-duct and the like passage in the spraying device, in combination with an air-compressor, a storage-chamber for the compressed air, mechanism for operating the compressor carried by said chamber, and flexible-pipe connections connecting the chamber with the aforesaid tank and the latter with the air-passage in the spraying device, for the purpose set forth.

4. An apparatus such as described comprising a closed tank adapted to contain air under pressure, an open paint-receptacle in said tank, a paint-delivery duct opening near the bottom of said receptacle and leading to

the outside of the tank, and a spraying device having two passages, one for paint and one for air adapted to be respectively connected with the aforesaid delivery-duct and with a source of compressed-air supply, for the purpose set forth.

5. An apparatus such as described, comprising a closed tank adapted to contain air under pressure, an open paint-receptacle suspended in said tank above the bottom thereof, a paint-delivery duct opening near the bottom of said receptacle and leading to the outside of the tank, and a spraying device provided with two passages one for paint and one for air, adapted to be respectively connected with the aforesaid paint-delivery duct and with a source of compressed-air supply, for the purpose set forth.

6. An apparatus such as described, comprising a closed tank adapted to contain air under pressure, an open paint-receptacle in said tank, a paint-delivery duct opening near the bottom of said receptacle and leading to the outside of the tank, and a spraying device having two passages one for paint and one for air, adapted to be respectively connected with the aforesaid delivery-duct and with a source of compressed-air supply, in combination with an agitator or stirrer for the paint-receptacle, for the purposes set forth.

7. An apparatus such as described, comprising a closed tank adapted to contain air under pressure, an open paint-receptacle in said tank, a paint-delivery duct leading from near the bottom of said receptacle to the outside of the tank, a spraying device having concentric passages for air and paint and a flexible pipe connected with the aforesaid paint-delivery duct and paint-passage, in combination with an air-compressor, a compressed-air chamber connected therewith and flexible pipes connecting the said chamber with the aforesaid tank and with the passage for air in the spraying device, for the purpose set forth.

8. An apparatus such as described, comprising a tank adapted to contain air under pressure, an open paint-receptacle contained in said tank, a stirring or agitating device consisting of a tubular open-ended agitator-shaft provided with suitable blades and extending nearly to the bottom of the paint-receptacle and to the outside of the tank, and a channeled handle on the outer end of said shaft, said handle provided with an outlet constructed for connection with a suitable paint-delivery pipe, for the purpose set forth.

9. In an apparatus such as described, the combination with the paint-conveying pipe and the source of paint-supply, of an intermediate pipe terminating in a stuffing-box, a strainer interposed in said pipe, and a tubular stuffing-box gland for the reception of the paint-conveying pipe, said gland provided with a handle and adapted to screw into the stuffing-box of said pipe, substantially as and for the purpose set forth.

10. In an apparatus such as described, a spraying device constructed to be held in the hand comprising a casting provided with two passages, one for paint and one for air, with 35
5 a purge or blow-off branch in communication with the passage for paint, and with a passage adapted to connect the purge or blow-off branch with the passage for air through said passage for paint, in combination with a valve or stop-cock adapted to control the flow of paint through its passage and the flow of air through the purge or blow-off branch, a pinion on the valve-spindle, and the spring-controlled toothed sector-lever in gear with said 40
10 pinion, for the purpose set forth.

11. In an apparatus such as described, a spraying device comprising two concentric nozzles, passages for paint and air leading to said nozzles, a rigid pipe-section connected 45
20 with each of said passages, said pipe-sections rigidly connected together and forming a handle for the spraying device, in combination with a source of paint-supply, a source of compressed-air supply and flexible pipes 50
25 connecting the paint and air passages in the spraying device with the source of supply of paint and compressed air, respectively, for the purpose set forth.

12. In an apparatus such as described, a 55
30 tank adapted to contain compressed air and provided near its upper end with interior inward projections or brackets, in combination with a receptacle for paint provided with a rim-flange adapted to seat on the aforesaid

projections, a cover adapted to close the open 35
end of the tank fluid-tight, and a paint-delivery duct extending from the cover near to the bottom of the paint-receptacle, for the purpose set forth.

13. In an apparatus such as described, the 40
combination with a spraying device constructed to be held in the hand and provided with separate passages for paint and air, a valve for controlling the flow of paint through said paint-passage and a purge or blow-off 45
branch leading from the air-passage to the atmosphere and intersecting the paint-passage, of a lever in reach of the fingers of the hand that holds the spraying devices, said lever adapted to move the valve so as to bring 50
the passage therein in line with said blow-off branch whereby the valve-passage can be freed from obstructions by a finger of the hand that holds the spraying device, substantially as set forth.

In testimony that we claim the foregoing as our invention we have signed our names in presence of two subscribing witnesses.
